[57] CLAIM

The ornamental design for a process control unit for a control panel mounted control station, as shown and described.

DESCRIPTION

FIG. 1 is a perspective view of a process control unit for a control panel mounted control station showing our new design;

FIG. 2 is a front elevational view thereof;

FIG. 3 is a rear elevational view thereof;

FIG. 4 is a top edge elevational view thereof; and

FIG. 5 is a bottom edge elevational view thereof.

The rear view of the device has no distinguishable features.

The broken lines are shown for illustrative purposes only.

FIG. 1

FIG. 2

FIG. 5

FIG. 4

FIG. 3
